DESIGN FOR A MAN'S DRESS SHIRT OR SIMILAR ARTICLE

Herbert H. Marble, Rockville Centre, N. Y.

Application October 19, 1934, Serial No. 53,688

Term of patent 14 years

To all whom it may concern:

Be it known that I, Herbert H. Marble, a citizen of the United States, and resident of Rockville Centre, Long Island, in the county of Nassau and State of New York, have invented a certain new, original, and ornamental Design for Men's Dress Shirts or Similar Articles, of which the following is a specification, reference being had to the accompanying drawing, forming a part thereof, and of which Figure 1 is a front view, and Fig. 2 a rear view of a man's dress shirt or similar article showing my new design.

The vertical-horizontal cross hatching indicates the direction of the warp and filling of the fabric.

The design consists in the reversed diagonal stripe arrangement at the front and back of the shirt as shown.

I claim:

The ornamental design for a man's dress shirt or similar article, substantially as shown and described.

HERBERT H. MARBLE.
